PRODUCTION OF LONG-CHAIN OLEFINS BY
CATALYTIC CRACKING OF PARAFFINIC
WAX

William I. Gilbert, New Kensington, and Charles W. Montgomery, Oakmont, Pa., assignors to Gulf Research & Development Company, Pittsburgh, Pa., a corporation of Delaware

No Drawing. Application June 22, 1945,
Serial No. 601,071

6 Claims. (Cl. 260—683)

1

This invention relates to a method of catalytic cracking and more particularly it relates to the catalytic cracking of paraffinic wax to olefins.

Olefins in the molecular weight range above gasoline, particularly if they are of straight chain structure, are highly desirable for use in the synthesis of special lubricants, rust inhibitors, and many other materials. Such olefins have been obtained prior to the present invention at relatively high cost from natural products. Cracking processes, both thermal and catalytic, have long been applied to hydrocarbons including paraffinic waxes, but by all these known methods the yield of higher boiling olefins from the cracking of paraffinic waxes has been low.

It is therefore an object of this invention to produce a high yield of olefins from paraffinic waxes and wax bearing oils.

It is a further object of this invention to produce a high yield of olefins in the C₁₂ to C₂₀ range from paraffinic wax.

It is a further object of this invention to provide an improved catalytic cracking process for the conversion of paraffinic waxes to olefins in the C₁₂ to C₂₀ range.

These and other objects are attained by the present invention wherein paraffinic waxes are subjected to cracking conditions in the presence of a catalyst comprising a hydrated magnesium silicate-calcium silicate compound. By the use of this catalyst it is possible to obtain a high yield of olefins in the C₁₂ to C₂₀ range composed predominantly of straight chain molecules.

The data in the table below summarize examples of runs in which 135° F. E. M. P. ASTM melting point paraffinic wax having an average molecular weight of 399 was charged at atmospheric pressure over granular hydrated magnesium silicate-calcium silicate compound at the temperatures and space velocities indicated in the table. The total product was then distilled at atmospheric pressure to 400° F. to remove the gasoline and the residue was distilled at a pressure of 10 mm. of mercury to a cut point of 392° F. The various fractions of approximately the molecular weights shown were removed and the olefin contents determined by bromine number. The total of these fractions has been called the oil fraction.

Table

Run No.	I	II	III	IV	V-VI
5					
Conditions:					
Temperature, °F.	850	815	820	845	900
Space Velocity	0.5	0.5	1.0	0.8	0.5
Throughput	1.0	1.0	1.0	0.8	1.0
Yields, wt. Per cent of Charge:					
Gas (C ₄ and lighter)	4.6	4.7	3.7	4.5	20.1
Gasoline (debut. 400° F. E. P.)	30.0	10.4	14.2	26.4	61.0
10 Oil Fraction (to 392° F. at 10 mm.)	16.6	10.9	9.2	15.5	12.3
Coke	0.2	0.3	0.2	0.2	0.3
Wax residue (recycle)	48.6	64.7	72.7	53.4	6.3
Efficiency (Oil Fraction / 1-Recycle) × 100	32.3	30.0	33.7	33.3	13.1
15 Bromine No. of gasoline	127.7	125	131	136.1	150.1
	Br. No.	Br. No.	Br. No.	Br. No.	Br. No.
20 Oil Fraction Inspection:					
Cut #1, init.-212° F. at 10 mm. (C12)	75.3	68.0	74.0	76.6	59.9
Cut #2, 212-257° F. at 10 mm. (C14)	54.4	51.7	55.6	60.5	36.4
Cut #3, 257-302° F. at 10 mm. (C16)	38.7	38.1	44.1	46.9	21.3
25 Cut #4, 302-348° F. at 10 mm. (C18)	26.6	25.2	27.7	32.0	12.4
Cut #5, 348-392° F. at 10 mm. (C20)	16.0	11.9	22.5	18.7	7.2
Residue	2.0	1.9	1.5	2.4	2.0
25 Per cent Olefins:					
Cut #1	70	72	78	81	63
Cut #2	67	63	68	74	45
Cut #3	54	53	62	66	30
Cut #4	42	40	44	50	20
Cut #5	29	21	39	33	13
30 Per cent Olefins in total oil fraction	57	51	60	63	32

It will be seen from the above table that the best yields of olefins can be obtained when operating at about 845° F. at a space velocity of 1.0. Lower temperatures result in a decreased oil yield although a high degree of unsaturation is maintained. Higher temperatures also decrease the oil yield and greatly increase the gasoline and gas yields while the olefin content of the oil is also reduced. Temperatures outside the examples (i. e., 815°-900° F.) are therefore not recommended and the temperature of 845° F. is the most preferable.

45 The effect of space velocity is not as pronounced as that of temperature but low space velocities decrease the olefin content of the oil, probably by hydrogen transfer, and thus a space velocity of from 0.5 to 2.0 has been found desirable and a space velocity of 1.0 is most preferable.

3

The efficiencies given in the table show the percentage of total conversion going to the C₁₂-C₂₀ oil fraction and are approximate values for the ultimate recycle yield. It will be noted also that the coke yields are extremely low, thus making catalyst regeneration easy.

The process of cracking may be carried out by any of a number of methods well known to the prior art of catalytic cracking and the apparatus which is used may vary, many types of apparatus being adaptable to the present invention.

The catalyst is a hydrated magnesium silicate-calcium silicate compound produced by the reaction of a hot solution of a magnesium salt of a strong acid upon calcium silicate for a time sufficient to effect only a partial conversion of the calcium silicate to magnesium silicate. The catalyst is more specifically described in U. S. Patent 2,163,525 to Lyle Caldwell. It has been found most preferable to use the catalyst in a granular form.

In the specification and claims, space velocities represent liquid volumes of reactant per volume of catalyst per hour. Throughput is the volumes of reactant per volume of catalyst before regeneration of the catalyst.

By paraffinic wax as used herein is meant pure paraffin waxes of varying melting point ranges as well as impure paraffinic waxes, such as crude scale wax and materials containing paraffinic wax, such as petrolatum or other waxy concentrates.

Thus we have described a new process for the production of a high yield of olefin hydrocarbons, particularly in the C₁₂ to C₂₀ range by the cracking of paraffinic wax in the presence of a hydrated magnesium silicate-calcium silicate compound.

What we claim is:

1. A process for producing olefin hydrocarbons of twelve to twenty carbon atoms per molecule from paraffinic wax which comprises subjecting the paraffinic wax under catalytic cracking conditions to contact with a catalyst comprising a hydrated magnesium silicate-calcium silicate compound at a temperature in the range of 815° to 900° F.

2. A process for producing olefin hydrocarbons of twelve to twenty carbon atoms per molecule from paraffinic wax which comprises subjecting the paraffinic wax under catalytic cracking conditions to contact with a catalyst comprising a hydrated magnesium silicate-calcium silicate compound at a liquid space velocity in the range 0.5 to 2.

3. A process for producing olefin hydrocarbons of twelve to twenty carbon atoms per molecule

4

from paraffinic wax which comprises subjecting the paraffinic wax under catalytic cracking conditions to contact with a catalyst comprising a hydrated magnesium silicate-calcium silicate compound at a temperature in the range of 815° to 900° F. and at a liquid space velocity in the range 0.5 to 2.

4. A process for producing olefin hydrocarbons of twelve to twenty carbon atoms per molecule from paraffinic wax which comprises subjecting the paraffinic wax under catalytic cracking conditions to contact with a catalyst comprising a hydrated magnesium silicate-calcium silicate compound at a temperature in the range of 815° to 900° F. and at a liquid space velocity in the range 0.5 to 2.0 and subsequently fractionally distilling to obtain the product boiling between 212° F. and 392° F. at a pressure of 10 mm. of mercury.

5. A process for producing olefin hydrocarbons of twelve to twenty carbon atoms per molecule from paraffinic wax which comprises subjecting the paraffinic wax under catalytic cracking conditions to contact with a catalyst comprising a hydrated magnesium silicate-calcium silicate compound at a temperature of about 845° F. and a liquid space velocity about one.

6. A process for producing a high yield of straight chain olefin hydrocarbons of 12 to 20 carbon atoms per molecule from paraffinic wax with an accompanying low coke yield, which comprises subjecting a paraffinic wax under catalytic cracking conditions to contact with a catalyst comprising a hydrated magnesium silicate-calcium silicate compound at a temperature of about 845° F., a liquid space velocity of about one and subsequently fractionally distilling to obtain the product boiling between 212° F. and 392° F. at a pressure of 10 mm. of mercury.
